UNITED STATES PATENT OFFICE.

SAMUEL D. CHAMBERS, OF BLUERIDGE, GEORGIA.

CULTIVATOR ATTACHMENT FOR PLOWS.

SPECIFICATION forming part of Letters Patent No. 787,355, dated April 18, 1905.

Application filed November 21, 1904. Serial No. 233,714.

To all whom it may concern:

Be it known that I, SAMUEL D. CHAMBERS, a citizen of the United States, residing at Blue-ridge, in the county of Fannin and State of Georgia, have invented a new and useful Cultivator Attachment for Plows, of which the following is a specification.

This invention relates to cultivator attachments for plows.

○ The object of the invention is to enable an ordinary bull-tongue plow to be converted into a cultivator by simply attaching thereto an auxiliary beam carrying earth-engaging implements.

5 Another object of the invention is to provide an attachment of the class referred to which shall possess superior advantages in point of simplicity, durability, and general efficiency.

○ With these and other ends in view, which will readily appear as the nature of the invention is better understood, the same consists in the improved construction and novel arrangement and combination of parts, which will be 5 hereinafter fully described, and particularly pointed out in the claims.

In the accompanying drawings has been illustrated a simple and preferred form of embodiment of the invention, it being, however,

○ understood that no limitation is necessarily made to the precise structural details therein exhibited, but that changes, alterations, and modifications may be made within the scope of the invention and without departing from the 5 spirit or sacrificing the efficiency of the same.

In said drawings, Figure 1 is a side elevation showing a plow equipped with the improved attachment. Fig. 2 is a horizontal sectional view taken on the line 2 2 in Fig. 1.

○ Fig. 3 is a rear elevation showing the plow-stock with the attachment applied thereto. Fig. 4 is a perspective detail view of the cuff or holder detached.

Corresponding parts in the several figures 5 are indicated by like characters of reference.

The improved attachment comprises a flat strip or bar of iron or steel 1, the central portion of which is bent or twisted so as to form a downwardly and forwardly inclined loop 2,

at the ends of which arms 3 and 4 are ex- 50 tended obliquely, respectively, in a forward and a rearward direction, said arms being disposed approximately in the same horizontal plane. The extremities of the arms 3 and 4 are bent or twisted so as to form downwardly 55 and forwardly extending feet or standards 5 and 6, each of which is perforated for the passage of a bolt 7, by means of which cultivator-blades 8 are secured in position upon the said standards. 60

The device is adapted to be attached for operation to the bifurcated stock or standard 9 of an ordinary plow, as shown in Fig. 1, where 10 designates the plow-beam and 11 one of the handles upon the near side of said beam. 65

12 and 13 are the bolts by means of which the standard is connected with the beam, said standard being provided in the usual manner with perforations 14 for the passage of a bolt 12 in order to enable the standard to be properly adjusted with relation to the beam. The standard carries the earth-engaging implement 15, which is secured thereto by means of the heel-bolt 16.

In operation the auxiliary bar or beam 1 is 75 adjusted, by means of the loop 2, upon the standard 9, said loop being made of a proper size to fit neatly upon the standard. To retain the auxiliary beam in position upon the standard, a cuff or holder 17 is employed, said

80 cuff consisting of a plate 18, adapted to fit between the side members 19 19 of the plow-standard and provided at its front end with a downturned lip 20, adapted to engage the front

85 side of the lip 2, and at its rear end with a downturned plate 21 of sufficient width to engage the rear side of the plow-standard. The lip 20 and the plate 21 are provided with perforations 22 for the passage of a bolt 23, whereby the device is firmly secured in position, said

90 bolt being also extended through a perforation in the loop 2 of the auxiliary beam 1. The cuff or holder 18 is preferably constructed of steel or material sufficiently resilient to

95 permit the lip 20 when the bolt 23 is tightened to be compressed upon the front side of the loop 2, thereby causing the attachment to be retained in position with the utmost secur-

ity and in such a manner as to prevent lateral swaying or wabbling when the device is in operation.

From the foregoing description, taken in connection with the drawings hereto annexed, the operation and advantages of this invention will be readily understood. The construction is extremely simple and inexpensive, and it will be noticed that the edge of the strip or bar constituting the auxiliary beam is exposed to the line of strain at all points, thereby enabling the device to resist any strain to which it may reasonably be subjected.

By the use of this improved attachment an ordinary plow may be quickly transformed into a cultivator for hilling up rows of plants, for eradicating weeds, and the like. Owing to its lightness and the ease with which it may be handled, it is especially fitted for sidehill work.

When not required to be used, the device may be readily separated from the plow, and the latter does not require to be prepared for the reception of the attachment by perforating the standard thereof for the reception of the bolts and the like, whereby it would be unnecessarily weakened.

Having thus described the invention, what is claimed is—

1. In combination with a plow having a bifurcated standard, of an auxiliary beam having a loop externally engaging said standard and a holder fitted between the side members of the standard, said holder having a downturned lip engaging the front side of the loop and a downturned plate engaging the rear side of the standard; and connecting means. 3c

2. The combination of a plow having a bifurcated standard, an auxiliary beam having a loop externally engaging said standard, a resilient cuff constituting a holding device, said cuff including a body fitted between the members of the standard, a downturned lip engaging the front side of the loop and a downturned plate engaging the rear side of the standard, and a connecting-bolt. 4c

In testimony that I claim the foregoing as my own I have hereto affixed my signature in the presence of two witnesses.

SAMUEL D. CHAMBERS.
